UNITED STATES PATENT OFFICE.

LAWRENCE GRIFFITH, OF YONKERS, NEW YORK.

TOBACCO-BOX.

1,178,715.

Specification of Letters Patent. Patented Apr. 11, 1916.

Application filed July 13, 1915. Serial No. 39,560.

To all whom it may concern:

Be it known that I, LAWRENCE GRIFFITH, a citizen of the United States, and a resident of Yonkers, in the county of Westchester and State of New York, have invented certain new and useful Improvements in Tobacco-Boxes, of which the following is a specification.

For the accommodation of pipe smokers, 10 tobacco is put up in the form of cartridges, each cartridge forming a charge for a pipe bowl. These charges are usually arranged in the form of a cylinder or roll, each roll containing a number of cartridges. These 15 rolls are ordinarily placed in a flat box, and after several of them have been removed the remaining charges and rolls are more or less loose in the box and are liable to be knocked about in the box and broken or 20 otherwise damaged.

One of the main objects of this invention is to provide a box specially adapted for containing these pipe cartridges or charges, means being provided to hold each individual roll or cylinder of charges independently, whereby upon the removal of a portion of the charges the remainder will be held in position and prevented from being knocked about in the box. Ordinarily these 25 boxes of charges are carried in the pocket, and if the charges are loose therein they soon become loosened or broken and are not in good condition for use.

Another object of the invention is to provide means whereby the individual rolls or charges may be readily removed from the box. When these boxes are packed, the rolls or charges are forced therein with considerable pressure in order to keep the tobacco in prime condition for as long a 40 period as possible. For this reason it is desirable to provide some means for ready removal of the charges without injury to any one of the cartridges.

45 There are other objects and advantages of the invention which will appear hereinafter.

In the drawing Figure 1 is a side elevation of a tobacco box constructed in accordance with the invention; Fig. 2 a vertical sectional view thereof showing the charges in position therein; Fig. 3 a bottom plan of the box; Fig. 4 a transverse sectional view thereof; and Fig. 5 a view similar to Fig. 4, showing a slightly modified construction.

55 Referring to the various parts by numerals, 1 designates the box body, 2 the

bottom thereof and 3 the usual hinged cover. The body of the box is preferably formed with the round end portions 4 and the parallel sides 5. The box is preferably of a 60 thickness equal to the diameter of one of the rolls or charges, so that said charges will fit closely within the box. The round end portions 4 are of the same radius as the cylindrical charges or cartridges so that one roll 65 of cartridges will fit tightly in each end portion 4. The body of the box is formed with longitudinally extending parallel inwardly projecting ridges 6. The surfaces of these ridges are concave and are of the same 70 radius as the tobacco charges. As shown in the drawing the box is adapted to contain four rolls of charges, the ridges 6 projecting inwardly from each side 5 of the box and lying between the rolls of charges on both 75 sides of the box. These ridges and the end portions of the box form compartments, each adapted to receive and independently hold a roll of pipe cartridges.

In the bottom of the box is formed a 80 series of comparatively small apertures 7 directly beneath each roll of cartridges as indicated clearly in Fig. 2. When it is desired to remove a cartridge from the box a finger may be inserted in any one of said 85 apertures and the roll of cartridges directly thereover will be forced out of the top of the box sufficiently to permit its upper end to be firmly grasped. This makes a very convenient method of withdrawing the rolls 90 of cartridges even though they may be packed in the box under considerable pressure.

The ridges 6 may be formed by forcing 95 inwardly the metal of the sides of the box; the box at its upper and lower edges retaining its original shape to facilitate the attachment of the cover and the bottom pieces, as shown in Figs. 1 and 4. It will be readily understood, however, that if desired the 100 outer surface of the box may be maintained smooth and the ridges 6^a formed by inserting grooved and ribbed pieces 8, the ridges of said pieces forming the divided ridges 6^a to independently hold the rolls of tobacco 105 charges. The ribbed and grooved pieces 8 may be secured to the inner surfaces of the flat sides of the box, as shown in Fig. 5.

With a box constructed as described, and as shown in the drawing, any desired roll of cartridges may be removed without disturbing the other rolls, and all danger of the re-

maining cartridges being knocked about and broken after a portion of the cartridges have been removed, is avoided.

What I claim is:

5. A tobacco box adapted to contain pipe charges in the form of cartridges, formed of a body part having straight parallel sides at its bottom and top and having rounded ends, a bottom rigidly secured to said body
- 10 part, a cover hinged to the top of the body part, inwardly projecting parallel ridges formed in the sides and extending from a point near the bottom of the box to a point near the top thereof, the inner surfaces of said ridges being concave and forming parts of the walls of cylindrical compartments within the box, the rounded ends of the box forming parts of the walls of the end compartments, each compartment being adapted to receive pipe charges, the bottom of the box being formed with apertures registering with the lower ends of the compartments, said apertures being smaller in diameter than the diameter of the compartments.
- 15 20 25 2. A tobacco box adapted to contain pipe

charges in the form of cartridges, formed of a body part having straight parallel sides at its bottom and top and having rounded ends, a bottom rigidly secured to said body part, a cover hinged to the top of the body part, 30 inwardly projecting parallel ridges formed on the inner surfaces of the sides and extending substantially from the bottom to the top of the box, the inner surfaces of said ridges being concave and forming parts of 35 the walls of substantially cylindrical individual compartments within the box, each compartment being adapted to receive a roll of cartridges or pipe charges, the rounded ends of the box forming parts of the walls 40 of the end compartments, the bottom of the box being formed with apertures which register with the lower ends of the compartments, said apertures being smaller in diameter than the diameter of the compartments. 45

In testimony whereof I hereto affix my signature in the presence of two witnesses.

LAWRENCE GRIFFITH.
